STANLEY D. LIVINGSTON, OF FREEPORT, NEW YORK, ASSIGNOR TO EISEMANN MAGNETO CORPORATION, OF NEW YORK, N. Y., A CORPORATION OF NEW YORK.

IMPULSE STARTER FOR MAGNETOS.

Application filed April 1, 1926. Serial No. 99,049.

My invention relates to impulse starters for ignition magnetos, and its object is to provide certain novel features by which the operation of such devices is considerably improved.

In prior impulse starters utilizing centrifugal pawls for holding and releasing the driven member, there has always existed the inherent objection of changes in the cut-out speed with continued service. Let me explain more fully what I mean. It is well known that in impulse starters as heretofore constructed, there is a fixed catch-plate engaged by a centrifugal pawl on the driven member for holding the latter stationary while the driving member is rotated to wind up the spring. In those previous devices, the engagement between the catch-plate and pawl has always been along two sharp lines or edges formed by straight shoulders provided on those two parts. When the speed of the engine is sufficiently high, the pawl flies out of locking engagement with the catch-plate and the impulse starter operates like a coupling. However, with those sharp engaging edges on the catch-plate and pawl, the latter would continue to engage the catch-plate even when the contact point was only a few thousandths of an inch, and the unit would function as an impulse starter. At a slightly higher speed, no engagement would occur and the unit would "cut out", as the engineers say, and act simply as a coupling. But if the unit should continue to operate at this critical speed, a new hours' service would wear off the sharp point of engagement and this would change the cut-out speed. By the critical speed I mean the speed at which the pawl just engages the catch-plate and alternately catches and misses. I found, for instance, by actual tests that when a unit of the type referred to was operated as an impulse starter for about 100 hours, the wear which always took place on the pawls and catch-plate invariably changed the point of cut-out. Further, I observed that, if the impulse starter was operated at a certain critical speed, the wear at the engaging points on pawl and catch-plate would be excessive and in a few hours the unit was completely destroyed so far as service was concerned.

The present invention is for the purpose of completely removing the foregoing objection and disadvantage in prior impulse

starters, and to that end I provide a construction in which the engaging surfaces on the pawl and catch-plate are rounded or beveled in such a way as to eliminate any hair-trigger adjustment. The pawls either engage the catch-plate or they slide off. There is no wear at the critical point of engagement, and therefore the point of cut-out is not varied by use. I have demonstrated this by severe tests.

The practical advantages of my invention will be fully understood from a detailed description of the impulse starter shown in the accompanying drawings, in which

Fig. 1 is a side elevation of an impulse starter constructed in accordance with my invention, the cover surrounding the parts being shown in section;

Fig. 2 is a face view of Fig. 1;

Fig. 3 is a longitudinal section on line 3—3 of Fig. 2;

Fig. 4 is a section on line 4—4 of Fig. 1, showing the construction and mounting of the pawls, one of which is in engagement with a fixed catch-plate;

Fig. 5 is a transverse section on line 5—5 of Fig. 1, showing the interior of the cup-shaped driving member;

Fig. 6 is a fragmentary plan view in section on line 6—6 of Fig. 5, showing how the cover is held in position;

Fig. 7 is an enlarged view showing the locking pawl in engagement with the catch-plate; and

Fig. 8 is a view similar to Fig. 7, showing the pawl in position to slide off the catch-plate at the cut-out speed.

The impulse starter shown in the drawings comprises a driving member 1 and a driven member 2. The driving member 1 is in the form of a cylindrical casing or cup, and the driven member 2 consists of a disk carrying a pair of weighted pawls 3 and 4 pivoted on studs 5. As seen in Fig. 3, the studs 5 project rearwardly, and the pawls 3 and 4 are mounted outside the housing 6 formed by the members 1 and 2. The driven disk 2 is rigidly fixed on a hub 7, which is keyed on the projecting end 8 of the magneto shaft. The magneto structure need not be described, since the magneto forms no part of my invention, and I have therefore shown only a portion of the magneto frame M. The hub 7 is held against axial movement on the magneto shaft by a cup-shaped washer 9.

and a screw 10. The washer 9 has an annular flange or shoulder 11 which retains the driving cup 1 on the cylindrical extension 7' of hub 7. The member 1, which is rotatably mounted on hub 7, is provided with radial coupling lugs 12 for engaging a suitable driving member (such as a coupling disk) operated at the proper speed from the engine shaft. It will be seen from the foregoing 10 that the driving member 1 is rotatably mounted on the magneto shaft, and that the driven member 2 is always rigidly connected with the magneto shaft.

In the chamber 6 formed by the members 15 1 and 2 is mounted a strong coil spring 13 for releasably connecting the members 1 and 2, as will presently be explained in detail. The outer end 13^a of spring 13 is hooked over the lug 14 on casing 1, and the inner 20 end 13^b of the spring is inserted in a slot in the hub 7. The lug 14 may be formed integral with member 1 by upsetting the metal, as indicated in Fig. 5. In assembling the parts 1, 2 and 13, the spring is 25 placed under initial tension.

Each pawl 3 and 4 has a weighted trailing end 15 and a tip 16. The trailing end 15 of each pawl has a locking shoulder 17 arranged to engage a fixed stop 18, usually 30 called a catch-plate. The pawls are preferably made of heavy flat metal free from lateral bends, so as to have increased strength and durability. By means made flat, the pawls can be punched from a thick 35 piece of hardened steel. Attention is called to the fact that the stop shoulder 17 of each pawl is formed with a rounded edge 17'. The catch-plate 18 is provided at one or both ends with a locking shoulder 19 adapted to 40 be engaged by the shoulder 17 of the pawl to hold the driven member 2 against movement. The locking shoulder 19 has a bevelled or rounded edge 19' over which the rounded point 17' of the pawl is adapted 45 to slide at the cut-out speed of the unit, as will be more fully explained later on.

The fixed stop or catch 18 is a piece of hard steel rigidly secured to a plate 20, as by welding or otherwise. Plate 20 is attached to the magneto frame by screws 21 or other fastening means. An opening 22 in plate 20 allows the magneto shaft to project therethrough.

The driving cup 1 is provided with a pair 55 of peripheral or arcuate projections 23 which extend axially over pawls 3 and 4 into radial alignment therewith. Whichever pawl engages the catch-plate 18, its tip 16 projects into the path of the projections 60 23, as may be seen from Fig. 4. Therefore, when either projection 23 moves over the tip of the locking pawl, it forces the same inwardly and thereby rocks the pawl out of locking contact with stop 18. One or both 65 ends 23' of projections 23 are preferably bevelled to facilitate engagement with the tip of the pawl.

The driven member 2 is provided with a pair of radial projections 24 extending over an arc α — β . When the parts are assembled 70 in normal position, the trailing ends of the projections 23 on the driving member 1 are held against the leading ends α of the projections 24 on the driven member 2 by the normal tension of spring 13. When for any 75 reason the spring 13 should break or otherwise become inoperative, the leading ends of projections 23 engage the trailing ends β of projections 24. The projections 24 on the driven member 2 also act as stops against 80 the inward movement of the driving cup 1 on hub 7, as may be observed in Fig. 1. In other words, the driving cup is rotatably held on hub 7 between the flange 11 of washer 9 and the projections 24 of disk 2. 85

The driving cup 1 is surrounded by a cylindrical cover 25 removably secured to the back-plate 20, which is provided with an annular flange or shoulder 20' for seating the rear edge of the cover. This is best 90 shown in Figs. 1 and 3. The front edge 26 of the cover is shaped as an annular hollow bead in which is held a ring 27 of felt or other soft dust-excluding material. As seen from Figs. 1 and 3, the ring 27 projects beyond the metal of the cover into contact with the driving cup 1, whereby a practically 95 dust-proof casing is formed around the impulse starter. This is of particular advantage on vehicles operating in dusty regions, such as tractors, where abrasive dust quickly accumulates on exposed parts, and not only interferes with their proper operation, but shortens their life as well. The felt ring 27 is securely fastened in position by slightly 100 dishing the outer rim or flange 28 of the cover, as clearly indicated in Figs. 1 and 3. To permit quick and easy positioning and removal of cover 25, I use a pair of spring clamps 29 pivoted at 30 to lugs or ears 31 on plate 20. Locking hooks 32 formed on clamps 29 are adapted to snap over the recessed rim of flange 26 for holding the cover firmly in position. Finger extensions 33 allow 105 easy manipulation of the clamps. 110

The operation of the impulse starter above described is as follows:

When the driving member 1 is rotated in the direction indicated by the arrow x in Figs. 1 and 4, the spring 13 is wound up, because the pawl 3 engages the catch-plate 18. This winding up of the spring continues until one of the projections 23 on the driving cup 1 strikes the tip 16 of the locking pawl, whereupon the shoulder 17 is moved out of 120 contact with catch-plate 18, and the tensioned spring suddenly impels the driven member 2 in the direction of arrow y (Fig. 4). Since member 2 is fixed on the magneto shaft, the latter receives a sudden rapid movement suf- 125 130

ficient to generate the required sparking current. If the engine does not fire on the first impulse of member 2, the operation described is repeated until the magneto generates the starting spark. When the engine attains a certain speed, the weighted ends of pawls 3 and 4 are thrown out of the path of catch-plate 18, and the spring 13 acts as a resilient coupling between the driving cup 1 and the driven disk 2. That is so because, as previously explained, the spring normally holds the forward ends of projections 24 on driven member 2 against the rear ends of projections 23 on the driving cup. Now, between the lower speed at which the pawl is locked to the catch-plate and the cut-out speed at which the pawl clears the catch-plate, there is a critical speed when the pawl just engages the catch-plate. I might say that at this speed the pawl flutters into and out of contact with the catch-plate, alternately missing and catching. In prior impulse starters, where the pawl and catch-plate engage along straight edges with sharp ends, the cut-out speed depends upon a hair-trigger engagement that changes with the wear of the sharp engaging edges on pawl and catch-plate. Hence, in those previous devices, a uniform cut-out speed is impossible under continued service. This objectionable feature is entirely overcome by the novel construction of locking shoulders on catch-plate and pawl. Referring to the enlarged views of Figs. 7 and 8, the shoulder 17 of the pawl at lower speed either fully or partially engages the shoulder 19 of the catch-plate, as shown in Fig. 7. In either case, the pawl is positively locked to the catch-plate. As the speed increases, the amount of engagement between the surfaces 17 and 19 decreases to a point where only the bevelled or rounded edges 17' and 19' meet, whereupon the pawl slides off the catch-plate and the unit ceases to function as an impulse starter. This position of the parts is illustrated in Fig. 8 on an exaggerated scale. I might explain that Figs. 7 and 8 (in the drawings as originally filed) show the pawl and catch-plate about twice the actual size, while the other figures show the impulse starter in full size. Comparing Figs. 7 and 8, it will be clear that the pawl either positively engages the catch-plate or it slides off. There is no wear at the critical point of engagement and consequently the cut-out speed remains unchanged by continued use. I have operated impulse starters of this new construction at speeds that were previously considered critical (i. e., where the pawl alternately catches and misses), and this severe test showed a uniform cut-out. In the particular embodiment

illustrated in the drawings and which I have actually used in practice under working conditions, the rounded edge 17' on the pawl is formed on a radius of about 0.047 inch. I mention this by way of example and not as a limitation. By adjusting the weight of the pawl, it is possible to obtain a cut-out at some predetermined speed. There is no wear on the rounded surfaces 17' and 19' when they engage, (see Fig. 8) because there is no load on the pawl for the reason that the latter slides off the catch-plate instead of winding up the spring.

What I claim as my invention is:

1. In an impulse starter for magnetos, the combination of a driving member, a driven member connected to the magneto shaft, a spring connected between said members, a centrifugal pawl pivoted on said driven member and provided with a shoulder, a fixed stop also provided with a shoulder, each of said shoulders consisting of a straight locking surface and a rounded cut-out edge, said shoulders being so arranged that normally and at low speeds the locking surfaces engage to hold the driven member temporarily against rotation while the driving member is operated to place said spring under tension, and means for releasing said interlocking surfaces to cause the tensioned spring to impart a rapid rotation to said driven member, said rounded edges of the locking shoulders causing said pawl automatically to slide out of engagement with said stop at predetermined cut-out speed.

2. In an impulse starter for magnetos, the combination of a driving member, a driven member connected to the magneto shaft, a spring connected to said members, a pawl pivoted on said driven member, said pawl consisting of a flat piece of metal having a weighted trailing end provided with a shoulder, a fixed stop also provided with a shoulder, each of said shoulders consisting of a straight locking surface and a rounded cut-out edge, said shoulders being so arranged that normally and at low speeds the locking surfaces engage to hold the driven member temporarily against rotation while the driving member is operated to place said spring under tension, a projection on said driving member arranged to engage the tip of said pawl and rock the same to release said interlocking surfaces, so that the tensioned spring imparts a rapid rotation to the driven member, said rounded edges of the locking shoulders causing said pawl automatically to slide out of engagement with said stop at predetermined cut-out speed.

STANLEY D. LIVINGSTON.
